UNITED STATES PATENT OFFICE.

LESLIE E. FROST, OF PITTSBURGH, PENNSYLVANIA, ASSIGNOR TO WESTINGHOUSE ELECTRIC & MANUFACTURING COMPANY, A CORPORATION OF PENNSYLVANIA.

SPRAYING MACHINE.

Application filed July 30, 1920. Serial No. 400,234.

To all whom it may concern:

Be it known that I, LESLIE E. FROST, a citizen of the United States, and a resident of Pittsburgh, in the county of Allegheny and State of Pennsylvania, have invented a new and useful Improvement in Spraying Machines, of which the following is a specification.

My invention relates to spraying machines and more particularly to machines of the type that is adapted for spraying liquid shellac upon mica splittings.

Heretofore, the process of making mica wrappers has consisted in feeding a sheet of tissue paper or other suitable paper along a table. The paper was given a coating of shellac by brushing by hand and a layer of mica splittings applied manually. This operation was repeated until there were several alternate layers of shellac and mica splittings applied to the paper. Tissue paper was then laid over the last layer of splittings and the formed wrapper was rolled upon a drum located at the end of the table.

This method has proven to be slow and expensive as all of the steps were performed by hand.

One of the objects of my invention is to provide a machine of the character described that will automatically apply a thin and uniform coating of shellac to a strip of paper as the same is automatically fed under a spraying mechanism.

Another object of my invention is to provide means for confining and carrying away the vapor and fumes resulting from the spraying operation.

Another object is to provide a simple and efficient mechanism whereby one spraying nozzle may be caused to spray the entire width of the paper.

In the said drawings:

Fig. 1 is a view in side elevation of a machine embodying my invention.

Fig. 2 is a plan view of the machine of Fig. 1.

Fig. 3 is a transverse section on an enlarged scale on line III—III of Fig. 1.

Fig. 4 is an enlarged side elevational view of one of the central spraying stations, part of the side wall thereof being broken away so as to show the spraying mechanism.

Fig. 5 is a front elevation of the spraying nozzle and supporting carriage.

Fig. 6 is a side elevation of Fig. 5.

Fig. 7 is a plan view of the carriage and track showing the spray control mechanism.

Referring to the drawings, a table 1 is preferably formed of slatted structure and is adapted to support a strip of paper 2 which is continuously fed along the same from a roll 3' mounted near the end of the table.

Spraying stations A, B and C are arranged at spaced intervals along the table, each of which comprises a frame 3 which serves, also as the supports for the table 1. The portions of the frames above the table are provided with side and end walls 4 and 5, respectively, which form a hood or housing enclosing the spraying mechanism and which is provided with doors 4' through which access may be had to the spraying mechanism. The sides of the hood terminate at a point adjacent to the moving paper, allowing sufficient clearance to permit the strip to pass freely thereunder.

A track consisting of parallel and transversely extending rails 6 and 7 secured to the ends walls 5 of the hood support a laterally reciprocating carriage 8 at a suitable distance above the paper. The carriage is formed with ears 9 to which are secured the ends of cables or wire ropes 10 which extend in opposite directions therefrom and which pass over pulleys or sheaves 11 that are mounted on brackets 12 fixed to the end walls of the hood and thence extend downwardly around pulleys 13 carried by brackets 14 mounted on a cross bar 15 secured to the frame 3, from which point they extend inwardly and are secured at their ends to upwardly extending ears or projections 16 of the carriage 17. The carriage 17 is slidably mounted for transverse movement upon a track comprising parallel rails 18 supported at each end in brackets 19 secured to horizontally disposed angle bars 20, which form a part of the frame 3.

A double-acting screw-threaded shaft 21 is mounted in the brackets 19 and at a point between and slightly below the track rails 18 and is adapted to be engaged by a two-way screw-threaded portion 22 depending from the carriage 17. A spur gear 23 is keyed to one end of the shaft 21 and is driven by means of a pinion 24 fixed to a shaft 25. One end of the shaft 25 is supported in the bracket 19 and the other end thereof is mounted in a bracket 26 supported by hori-

zontally disposed channel bars 27 which is, in turn, supported by the angle bars 20 of the frame. The inner extremity of the shaft 25 has a bevelled pinion 28 fixed thereto which meshes with, and is driven by, a similar pinion 29 keyed to a horizontally extending drive shaft 30.

The carriages of the spraying stations A and C are actuated by means of cables 31 which are also attached to the sliding carriage 17 and which pass around pulleys 32 and 33 mounted in the brackets 14 and 12 respectively, from whence they extend in opposite directions and are secured at their other ends to similar spraying carriages at their respective stations.

The carriages 8 preferably comprise a rectangular frame provided with a longitudinal opening 34 within which are mounted flanged rollers 35 adapted to ride upon the rail 7. The upper portion of the carriage frame is further provided with a bracket 36 which is slidably mounted therein for horizontal movement and carries a roller 37 adapted to be yieldably maintained in rolling contact with the side of the rail 6 by means of a coil spring 38. The roller slide is formed with a pin or rod 39, normally in contact with one arm of a bell crank lever 40, the other arm of which is pivotally connected to a link 41 which actuates the valve stem of an atomizing or spraying nozzle 42 normally held closed by means of a coil spring 43.

The rail 6 is formed with recesses or notches 44 at each end and in the path of the roller 37. When the carriage reaches the end of its travel in both directions, the rollers 37 enter the recess 44 under the action of the spring 38 and cause the pin 39 to release the bell crank lever 40 which permits the valve of nozzle 42 to be closed by the action of the coil spring 43 and temporarily shuts off the spray.

Air is supplied under pressure to the nozzle 42 by a pipe 45 leading from a source of supply, not shown, the suction of which siphons liquid shellac through a pipe 46. The end of the pipe 46 is constantly submerged in a tank 47 of liquid shellac which extends the entire length of the travel of the carriage 8 across the table.

The hood enclosing the spraying mechanism confines the suspended particles of shellac and the fumes thereof so that the former may gradually settle upon the moving paper and the latter may be drawn out of the hood and carried away by means of horizontal flues 48 arranged close to the paper and adjacent to the openings under the sides 4 of the hood. The flues 48 are each provided along the bottom thereof with relatively narrow slots 49 and the suction is regulated by means of valves or dampers 50. The flues 48 communicate with a common

exhaust pipe 51 which extends beneath the table and which in turn communicates with a suitable suction device or fan 52.

In operation, a sheet of fish paper is fed along the table and under the spraying station A. The power is applied from a suitable source, not shown, so as to cause the screw threaded shaft 21 to rotate. The sliding carriage 17 is thus caused to move from side to side across the table and, through the medium of the cables 10, cause the spraying carriage 8 to move similarly across the table, but in an opposite direction. As the carriage 8 reaches the end of its travel in one direction, the roller 37 engages the notch 44 in the rail 6 and causes the spray to be temporarily cut off. As a reverse movement of the carriage commences, the roller 37 is forced out of the notch, thereby causing the valve to be opened, permitting the spray to be again directed upon the paper.

As the moving paper and its first coat of shellac emerges from the opposite side of the spraying station A, a layer of mica splittings is applied thereto by hand. The strip continues in its travel and passes under the spraying station B where a second coat of shellac is applied, this time to the layer of mica splittings. A third coat of shellac and layer of mica splittings are applied in the same manner at station C and tissue paper is then applied to the top layer of splittings from a plurality of rolls 53. The entire wrapper is then rolled upon a relatively large drum 54 mounted at the end of the table.

I claim as my invention:

1. A spraying machine having, in combination, a movable spraying device, means for causing material to be sprayed to pass thereunder, and means for causing the spraying device to move laterally across said material.

2. A spraying machine having, in combination, a movable carriage, a spraying device mounted on said carriage, a support adjacent said carriage, means for feeding material to be sprayed along said support, and means for causing said carriage and spraying device to move across the path of said material.

3. A spraying machine having, in combination, a table, means for feeding a strip of material along said table, a spraying device located above the table and over the path of the material and means for causing said spraying device to move laterally across the path of said material.

4. A spraying machine having, in combination, a table, means for feeding a strip of material to the same, a spraying device located above said table and in the path of said material, means for actuating said spraying device to move the same laterally

across the material, means for confining and means for carrying away the fumes of the spray.

5. A spraying machine having, in combination, a support, means for feeding a sheet of material along said support, a plurality of spraying stations arranged along said support and over the path of said material, movable spraying devices arranged at each 10 station, adapted to direct a spray upon said material, and means for moving said spraying device transversely to the direction of movement of said material.

6. A spraying machine having, in combination, a table, means for feeding a sheet 15 of material along said table, a plurality of independent spraying devices mounted on movable carriages at intervals along said table and over the path of said material, and means for causing transverse movement of 20 said spraying devices to spray the entire width of said material.

In testimony whereof, I have hereunto subscribed my name this 26th day of July, 1920.

LESLIE E. FROST.
